TINNING MACHINE

Filed Sept. 15, 1922

2 Sheets-Sheet 2

UNITED STATES PATENT OFFICE.

HARRY W. BUNDY, OF DETROIT, MICHIGAN.

TINNING MACHINE.

Application filed September 15, 1922. Serial No. 588,338.

To all whom it may concern:

Be it known that I, HARRY W. BUNDY, a citizen of the United States, residing at Detroit, in the county of Wayne and State 5 of Michigan, have invented certain new and useful Improvements in Tinning Machines, of which the following is a specification.

This invention relates to machine for tinning strips of metal, that is, covering a 10 strip of metal with a thin film of solder. The strip of metal is intended primarily to be used in the formation of a double ply tube. The tinning is for the purpose of providing a film of solder for sweating the 15 plies together when the tube has been formed into a plural ply cross section.

It is necessary in order to get high 20 grade tubing that the film of solder be applied to the metal strip in such a way as to provide a smooth film of uniform thickness and at the same time relatively imperceptible thickness. The machine about to be described is adapted to accomplish this purpose.

25 In the drawings:—

Fig. 1 is a vertical longitudinal section of the machine.

Fig. 2 is a detailed perspective of the transmission.

30 Fig. 3 is a detail of the sizing and pulling rolls.

Fig. 4 is a section taken on the line 4—4 of Fig. 3.

35 Fig. 5 is an enlarged view of the scraper. The bed of the machine and the supports may be of any convenient form. At one end a bracket *a* supports a plurality of removable spools *b* on which are carried the coils of metal strips. It is preferable 40 to have a plurality of spools so that the machine may go on uninterruptedly; by simply fastening the end of the exhausted spool strip to one of the other strips on one of the other coils, the work can go on without interruption. The ends of the strips of metal can be slotted and tongued so that 45 they can be easily fastened together by the operator while the machine is in motion.

The strip of metal *c* is drawn under the 50 guide roll *d* and over the guide roll *e* thence

down into a bath of cleansing acid *f*, such as muriatic acid. A roll *g* under which the strip *c* runs, holds the strip in the acid bath. The strip then runs upwardly between the adjustable rubber rolls *h* which pinches the strip and cleans off the acid. The strip then runs down and under the roll *i* in the solder bath *j*. The solder bath is kept constantly molten by the heat from the flames of the burner *k*.

The strip then passes upwardly between the pulling and sizing rolls *m*; these are detailed in Figs. 3 and 4. These sizing rolls are provided with flanges *n* and *o* at opposite ends of the two rolls, these flanges overlapping the unflanged ends of the other roll. They consequently limit the dimensions of the strip passing therebetween and serve to size up the strip to the proper shape at the edges.

The strip then passes upwardly out of the solder bath between the edges of the heated scraping dies *q* and *r*. The dies and strip are kept hot at this point by the burner 100. The driving and sizing rolls *m* serve, to a certain extent, to make the film of solder on the strip more or less uniform. However, if the strip were taken out of the machine at this point, it would be found that there were a considerable number of blotches of solder on the strip. The purpose of the scraping dies is to completely clean off this excess solder and make an even thin uniform film. The die *r* is a movable one for two purposes. One is to permit the removing of 80 the die when the joint between two strips is passing between the die and the other purpose is to have a gravity pressure of two dies toward each other. The handle *s* gives enough weight and leverage to this die to hold it against the strip with sufficient pressure to accomplish the scraping action desired.

From the scraping dies the strip passes over the guide roll *t* and down under the guide roll *u* in the water bath *v*. Above this bath the strip passes between the adjustable pressure rubber rolls *w* which serve to clean off the water and leave the strip bright and clean. The strip then passes over the guide 95 100

roll *x* on the spool *y*. There are two of these spools *y* so that when one spool fills up the strip may be transferred to the other spool.

The rolls *m* are the main driving rolls of the machine; these are positively driven by the bolt *z*. The receiving spool is also positively driven and serves to help pull the machine strip through the machine. The belt *z* is in turn driven by the belt 1. This belt 10 is connected up with a suitable transmission such as detailed in Fig. 2 so that the speed of the machine can be altered. The transmission shown in Fig. 2 is the so-called "Reeves" transmission. It works on the principle of having a belt and two conical section pulleys. 2 designates the driving pulley which is connected up by a power belt 3 with the source of power. 4 designates the driven pulley which is connected up with the belt 1 through a pulley 5. 6 designates a screw shaft which may be rotated to rock the walking beams. This rocking of walking beams causes one pulley to open up and the other pulley to close up thereby changing the driving ratio. The screw shaft 6 can be controlled from remote parts of the machine by chain 8 and the crank 9.

Of course the specific construction of the transmission is not material. The point is that some suitable transmission should be provided by which the machine may be speeded up or slowed down. It is very desirable to slow up the machine while the union between two strips is being effected. As already explained, when one of the metal strip spools is nearly exhausted, the operator connects up the end of the strip with the next spool to be fed into the machine. In doing this it is obviously necessary to slow up the machine. Preferably tongues and slots are provided at the ends. These can be interlocked and folded over so as to unite the two strips together. This permits one strip to follow the other through the machine. As the joint nears the scraping dies, the operator may temporarily lift the movable scraping die *r* to permit it to pass. As the joint comes to the receiving spool, the operator shears the strip at the joint and starts the work on to the other spool.

The solder bath roll *i* and the acid bath roll *j* are carried on the arms 10 and 11; these arms are parts of bent levers pivoted at 12 and 13. A hand lever 14 is connected up with one of these bent levers and a draft rod 15 connects the two bent levers. Consequently simply by shifting the hand lever 14 both rolls may be simultaneously lifted out of the two baths. The tin or solder bath is preferably about 70 parts of tin and 30 parts of lead.

What I claim is:

1. In a machine for the purpose specified, the combination of a soldering bath, a pair of width sizing rolls located adjacent to the soldering bath, and means for propelling a strip of metal through the soldering bath and through the sizing rolls. 65

2. In a machine for the purpose specified, 70 the combination of a soldering bath, a pair of flanged sizing and pulling rolls adjacent to the soldering bath, and means for guiding a strip of metal through the soldering bath and between the sizing and pulling rolls. 75

3. In a machine for the purpose specified, the combination of a soldering bath, a pair of sizing rolls located adjacent to the soldering bath and comprising rolls flanged only at one end, the flanges of the individual 80 rolls being on opposite ends and overlapping the unflanged ends, and means for propelling and guiding the metal strip through the soldering bath and through such rolls.

4. In a machine for the purpose specified, 85 the combination of a soldering bath, a pair of sharp scraping dies for scraping off the excess metal located adjacent to the soldering bath, and means for propelling and guiding a strip of metal through the soldering bath 90 and through the scraping dies.

5. In a machine for the purpose specified, the combination of a soldering bath, a pair of sharp scraping dies for scraping off the excess metal, one of which is stationary and 95 the other of which is movable, the latter being held in contact with the work by gravity, and means for propelling and guiding a strip of metal through the soldering bath and between the scraping dies. 100

6. In a machine for the purpose specified, the combination of a soldering bath, a pair of sizing rolls, a pair of scraping dies, and means for successively guiding and propelling a strip of metal through the soldering bath, the sizing rolls and the scraping dies. 105

7. In a machine for the purpose specified, the combination of a soldering bath, a water bath, means for propelling a strip of metal 110 successively through the soldering bath and the water bath, and means for scraping the excess metal off the strip, said means located between the soldering bath and water bath, and comprising a pair of dies arranged to 115 scrape off the excess metal.

8. In a machine for the purpose specified, the combination of a soldering bath, a water bath, means for propelling the strip of metal successively through the soldering bath and 120 the water bath, and sizing means located between the soldering bath and the water bath.

9. In a machine for the purpose specified, the combination of a soldering bath, a water 125 bath, means for propelling and guiding a

piece of metal successively through the soldering bath and the water bath, means for sizing the strip, and means for scraping the excess solder from the strip, said two last mentioned means being located between the soldering bath and water bath.

10. In a machine for the purpose specified, the combination of a soldering bath, a pair of scraping dies for taking off excess metal

located adjacent the soldering bath, independent means for heating said scraping dies and the strip at this point, and means for propelling and guiding the strip of metal through the soldering bath and through the scraping dies.

In testimony whereof I affix my signature.

HARRY W. BUNDY.
